UNITED STATES PATENT OFFICE.

JOHN P. COUGHLIN, OF CHICAGO, ILLINOIS.

WRENCH.

Application filed October 12, 1921. Serial No. 507,253.

To all whom it may concern:

Be it known that I, JOHN P. COUGHLIN, a citizen of the United States, and resident of Chicago, in the county of Cook and State of Illinois, have invented a certain new and useful Improvement in Wrenches, of which the following is a full, clear, concise, and exact description, reference being had to the accompanying drawings, forming a part of this specification.

My invention relates to wrenches and has for its principal object the provision of a device of this kind which may be used either as a pipe wrench or a monkey wrench.

It is another object of my invention to provide a device that will be quickly and easily adjustable to operate with equal facility as a pipe or monkey wrench.

Another object is to provide a device which is light in weight, neat appearing, and economically manufactured.

It is an important object of my invention to provide a device that embodies all of the foregoing features which may be easily and quickly assembled.

These and other objects of my invention will clearly appear by reference to the accompanying description and to the accompany drawings in which—

Figure 1 is a view in elevation of the preferred form of my device, some of the parts being shown in dotted lines to illustrate the construction,

Figure 2 is a view in elevation showing the position assumed by the parts when the device is used as a pipe wrench.

Figures 3 and 4 are respectively elevation and sectional views of a nut case forming a part of my improved device,

Figures 5 and 6 are detailed views, Figure 6 being taken on the line 6—6 of Figure 7,

Figure 7 is a detailed view of a plunger forming part of my device,

Figure 8 is a fragmentary view of a modified form of my device, and

Figure 9 is a sectional view taken on the line 9—9 of Figure 8.

Similar characters of reference refer to similar parts throughout the several views.

In the drawings 8 indicates a handle provided with a shank 9 having a stationary jaw 10, the shank 9 being provided with a sleeve 11, through which sleeve extends a movable shank 12 provided with teeth 13 and a jaw 14 formed integral with the shank 12. The shank 9 has an opening 15 cylindri-

cal in shape into which is adapted to be inserted a nut case 16, illustrated in Figures 1 to 4 inclusive. The nut case 16 is bifurcated at 17 for the reception of a threaded nut 18, the teeth of which are adapted for engagement with the teeth 13 of the shank 12. A pin 19 extends through apertures 20—20 formed in the nut case 16 to provide a rotatable mounting for the nut 18. The nut case 16 is slotted at 21—21 for the reception of the movable shank 12.

As illustrated most clearly in Figure 7, the shank 9 is recessed at 22 to receive a dog or plunger 23 and a helical spring 24. The stem 25 of the plunger 23 is notched at 26 so that the spring 24 may be bent and attached to the stem 25 by insertion in the notch 26. The base 27 of the spring 24 is of greater diameter than the remainder of the spring so that these convolutions may engage the walls of the recess 22 and hold the plunger in the position illustrated in Figure 7. With this arrangement, the spring 24 holds the plunger 23 in a position so that the shoulder 28 of the plunger engages the inner walls of the recess 22 and cannot be accidentally displaced. As best shown in Figures 5 and 6, the recess 22 is formed adjacent the wall 29 of the sleeve 11. Immediately adjacent the recess 24 is a shelf 30 upon which the face 31 of the plunger is adapted to rest when in the position illustrated in Figure 5.

It will be seen that the nut case 16 and the shank 12 are rotatably mounted so that when the plunger 23 lies within the recess 22, the device may be used as a pipe wrench for securing a firm grip on objects of cylindrical cross section. It will also be seen that the spring 24, acting upon the plunger 23, will act to keep the wrench jaws in a parallel relationship.

When it is desired to use the device as a monkey wrench, in which use the jaws 10 and 14 should remain in parallel relation to each other, the finger portion 23^a of the plunger 23 is lifted outwardly slightly to remove the shoulder 28 from the recess 22. The finger piece 23^a is then rotated to the position illustrated in Figure 5, in which position the face 31 of the plunger rests on the shelf 30. In this position the plunger 23 engages the shank 12 and prevents its rotation about the center of the nut case 16. It will be noted that the spring 24 is made of a length to hold the shoulder 28

within the recess 22 so that when the plunger is removed from the recess and the face 31 rests upon the shelf 30, the tension of the spring holds the plunger in this position to prevent accidental displacement. If desired, the shelf 30 may be inclined away from the recess 22 so that the face 31 tends to slide away from the recess to further prevent accidental displacement of the plunger.

In the assembly of the device just described, after attaching the spring 24 to the stem 25 of the plunger, the spring 24 is sprung into the recess 22, whereby the plunger 23 is held in position. The nut 18 is then disposed within the bifurcation 17 and the pin 19 extended through the apertures 20—20 and the nut 18. The nut case is then disposed within the opening 15, the slots 21—21 being aligned with the shank 12. Upon rotation of the nut 18, the threads thereof engage the teeth 13, whereby the shank 12, and thus the jaw 14, may be brought into operative relationship with the jaw 10.

In Figures 8 and 9, I have illustrated a modified form of device in so far as the nut case is concerned. In this modification, the shank 9 is provided with an opening 35, and to provide means for the reception of a large nut 36, the nut retaining means comprises a pair of segments 37—37 recessed at 38—38 to receive the studs 39—39 formed integral with the nut 36.

The segments 37—37 are slotted to receive the movable shank. It will be seen that the bridge portion of the other form of nut casing is eliminated to permit of a larger opening for the reception of the nut 36, this being desirable in the construction of a large size wrench.

In assembling the parts, the studs 39—39 are inserted in the recesses 38—38 of the segments 37—37, whereupon these members 45 may be placed in the opening 35. The slotted segments are aligned with the movable shank, and upon rotation of the nut 36, its threads engage the teeth of the shank. The nut 36 being held in the opening 35, 50 continued rotation thereof operates the shank.

What I claim is new and desire to secure by Letters Patent, is:

1. A wrench comprising a shank provided with a stationary jaw, a sleeve on said shank, a toothed movable shank provided with a jaw, said movable shank being mounted in said sleeve, a rotatable nut case in said first mentioned shank, a threaded nut 55 in said nut case arranged to co-operate with the teeth of the movable shank, said first mentioned shank being recessed to receive a dog, a spring disposed within the recess and held therein, said spring being attached to 60 said dog, said dog being provided with a

shoulder arranged, when the dog is within the recess, to prevent its accidental displacement, and a shelf on said shank adjacent the recess on which said dog may rest.

2. A wrench comprising a shank provided with a stationary jaw, a sleeve on said shank, a toothed movable shank provided with a jaw, said movable shank being mounted in said sleeve, a rotatable nut case in said first mentioned shank, a threaded nut 70 in said nut case arranged to co-operate with the teeth of the movable shank, said first mentioned shank being recessed to receive a dog, a spring disposed within the recess and held therein, and a shelf on said shank adjacent the recess on which said dog may rest.

3. A wrench comprising a shank provided with a stationary jaw, a sleeve on said shank, a toothed movable shank provided with a jaw, said movable shank being mounted in said sleeve, a rotatable nut case in said first mentioned shank, a threaded nut 80 in said nut case arranged to co-operate with the teeth of the movable shank, said first mentioned shank being recessed to receive a dog, a spring disposed within the recess, and a shelf on said shank adjacent the recess on which said dog may rest.

4. A wrench comprising a shank provided with a stationary jaw, a sleeve on said shank, a toothed movable shank provided with a jaw, said movable shank being mounted in said sleeve, a nut case in said first mentioned shank, a threaded nut in 90 said nut case arranged to co-operate with the teeth of the movable shank, said first mentioned shank being recessed to receive a dog, and a shelf on said shank adjacent the recess on which said dog may rest.

5. A wrench comprising a stationary shank having a jaw, a movable shank rotatably mounted in the stationary shank, a plunger disposed between the two shanks, one of said shanks being recessed to receive the plunger, said plunger arranged for depression into said recess, and a shelf adjacent the recess upon which the plunger may rest.

6. A wrench comprising a stationary shank, a movable shank rotatably mounted in the stationary shank, said shanks being provided with cooperating wrench jaws, and a member reciprocable between and transversely to said shanks to lock said movable shank against rotation.

7. A wrench comprising a stationary shank, a movable shank rotatably mounted in the stationary shank, said shanks being provided with co-operating wrench jaws, and a member reciprocable between and transversely to said shanks to lock said movable shank to permit only longitudinal travel of said movable shank.

8. A wrench comprising a stationary

shank, a movable shank rotatably mounted in the stationary shank, said shanks being provided with cooperating wrench jaws, and a lock longitudinally reciprocable and rotatably journaled between said shanks, which can be reciprocated to its outer position and then rotated to lock said movable shank against rotation.

9. A wrench comprising a stationary member, a movable member co-operating therewith, said members being provided with co-operating wrench jaws, and arranged to permit longitudinal movement and rotation with respect to the stationary member, and reciprocable means carried by the stationary member to prevent rotation of said movable member, and to permit longitudinal movement.

10. A wrench comprising a stationary shank, a movable shank rotatably mounted in the stationary shank, said shanks being provided with co-operating wrench jaws,

and reciprocable means provided in the path of normal rotation of the movable shank to permit the rotatable shank to be locked to prevent rotation.

11. A wrench comprising a handle, a housing adjacent one end thereof, a rotatable nut casing in said housing, a nut rotatably mounted in the nut casing, a rotatable and longitudinally movable jaw provided with a toothed shank co-operating with said nut, and a spring pressed member between the handle and the shank of the movable jaw, said spring pressed member being adapted upon rotation to prevent rotation of the movable jaw.

In witness whereof, I hereunto subscribe my name this 10th day of October, 1921.

JOHN P. COUGHLIN.
